United States Patent Office.

SAMUEL M. FIREY, OF CLEAR SPRING, MARYLAND.

Letters Patent No. 94,406, dated August 31, 1869.

IMPROVEMENT IN SEEDER AND FERTILIZER COMBINED.

The Schedule referred to in these Letters Patent and making part of the same.

To all whom it may concern:

Be it known that I, SAMUEL M. FIREY, of Clear Spring, in the county of Washington, and State of Maryland, have invented, certain new and useful Improvements in Seeding-Machines, Fertilizers, and Corn-Planters; and I do hereby declare the following to be a full, clear, and exact description thereof, reference being had to the accompanying drawings, which make part of this specification, and in which—

Figure 1 represents a plan or top view of a machine embracing my improvements;

Figure 2 represents a vertical longitudinal section of the same, through the line $x x$ of fig. 1;

Figure 3 represents a transverse section of the machine, taken at the line $y y$ of fig. 1, looking toward the front;

Figure 4 represents a vertical sectional view of the mechanism for operating the expandible pulley, by which the planting of corn is regulated, according to horizontal distance;

Figure 5 represents a plan or top view of the several parts shown in fig. 4;

Figure 6 represents a vertical section of one of the lower feeding-chambers, and its intermittently-winged feeder;

Figures 7 and 8 represent, respectively, a vertical transverse section and an elevation of one of the feeding-cylinders and its enclosing-case;

Figure 9 represents an elevation of the end of the hopper, and the gearing for operating the fertilizer;

Figure 10 represents a vertical sectional view of the same;

Figures 11, 12, 13, and 14, represent views of the rubber spring, and its connection with the drag-bars;

Figure 15 is a view in perspective of the seeding-tube, and its funnel-shaped or flaring mouth;

Figure 16, a view of the slotted plate for operating the fertilizing-slides;

Figure 17, a view of the cam, the weights, and the foot-levers; and

Figure 18, a view of one of the oscillating boxes of the rock-shaft of the fertilizing-hopper.

In the accompanying drawings—

A represents a rectangular frame, upon which the several parts of the machine are arranged and supported;

B, the supporting and carrying-wheels; and

C, the tongue, which is connected to the frame by two horizontal beams A², extending from the tongue C diagonally toward each side and rear of the machine, and to which are secured the inner ends of two short axles D of the supporting-wheels.

The diagonal beams A², being secured to the top of the frame A, and the axles to the under side thereof, the inner ends of these axles D are, therefore, curved

or turned upward to connect with these beams, and also to allow a horizontal rod, E, to be fitted into the lower part of each axle, and secured by screw-bolts a, fig. 3, and thus form a brace to the whole frame.

Upon this frame the hopper for the grain and fertilizer is mounted. It is divided into two compartments, one, F, for the grain, and the other, F², for the fertilizer.

Immediately beneath the hopper a horizontal shaft, G, is arranged, upon which are secured the feeding-cylinders H, so as to communicate, in the usual manner, with the openings in the grain-hopper.

Each of these cylinders is enclosed by a case, b, secured to the under side of the hopper, and divided by a partition into compartments, so as to divide the cells of the cylinders into two divisions for sowing or planting, as may be desired, as shown in figs. 7 and 8.

I construct these cylinders of India rubber, having their circumference fitted with iron bands d, to which ribs e, for dividing the cylinder into cells or chambers, are secured.

The body H of the cylinder, therefore, being of rubber, will yield to resistance in any direction, while the shaft G, upon which it is mounted, serves as a fixed centre.

The bands d, which surround it, are inelastic, and preserve its cylindrical form, but should any one of its ribs e come in contact with a gravel, or other hard substance, the whole body of the cylinder will yield, and thus carry the gravel out of the case with the grain.

The shaft G, being fixed to the rubber cylinder, of course the rubber will yield in any direction thereon, but the bands around its circumference, being inelastic, will always preserve the cylindrical form of the feeding-cylinder, while at the same time they will allow it to yield in regard to its axis of motion, either to one side or to the other, or on the surface of the cylinder, between the ribs e, and thus render the feeding-cylinder free from liability to be fractured, or to bind hard in its case from any cause whatever, and rendering it a universal-yielding cylinder, at the same time inelastic, to preserve its cylindrical form, and make it durable and light.

The ribs e, which divide it into cells or chambers, are placed upon its circumference, parallel with its axis, and they are notched or divided about the middle of their length, so as to receive the partition c within the case which encloses the cylinder, and thus divide it into two chambers, within which the ribs revolve.

That portion of the ribbed cylinder adapted to planting corn is made conical, so as to bring the corn out of its case more readily by yielding sideways, or in an inclined direction, as well as directly at right angles with its axis, as shown in fig. 8.

The drill-tubes I are united, in the usual manner,

to drag-bars, whose front ends are hinged to the front timber of the frame by horizontal bolts f , figs. 2 and 11, secured to the ends of brackets:

These drag-bars are arranged one within the other, the inner one, I^1 , within the outer one, I^2 , and the inner one is hinged to the drill-tube directly below the outer one, I^2 , while both are hinged at their front forked ends to the same bolt.

The outer drag-bar I^2 is hinged to the drill-tooth by a double joint, g , so as to allow the drill to trip in order to pass over obstructions.

The double joint is, however, maintained in its proper position with the drag-bars, and the drill prevented from tripping except when struck by a boulder or snag, by means of a rubber spring, h , arranged so as to constantly press the rear ends of the drag-bars apart in the usual manner.

The arrangement for securing and adjusting the spring h consists of a metallic strap, i , bent so as to form an inverted U, closed at top, and having its ends bent so as to form hooks, which embrace the sides of the outer drag-bar, and lock it thereto, as shown in fig. 13.

The spring h bears against the closed end of this strap i , while its lower end is seated upon a socket, i^2 , which is locked to a carriage, i^3 , which rests upon and is locked to the inner drag-bar I^1 , so that while the spring bears the outer drag-bar I^2 constantly upward, it also bears the inner one, I^1 , constantly downward.

The carriage i^3 has two projections i^4 , which embrace the drag-bar I^1 , so as to allow it to be adjusted thereon, and it is made with a series of notches on either side, into which projections from the seat fit, to lock the two together, and allow them to be adjusted nearer to or further from the drill, to increase or diminish the power of the spring, and to correct the deficiency in the size of the gum spring, arising from long usage and depression, as shown in figs. 11 and 14.

The strap i , the seat i^2 , and the carriage i^3 , thus arranged and connected, constitute an effective, simple, and durable spring-holder, which may be readily adjusted upon the drag-bars.

This adjustment of the spring h is effected by simply tilting, with the spring, the nut or seat i^2 , so as to release its projections from the notches of the carriage i^3 , and allow it to be moved and seated in another pair of notches, while at the same time the strap i is slid upon the double drag-bars I^2 , so that none of the parts of the spring need be removed from the drag-bars in making the proper adjustment.

The flexible tubes J conduct the grain from the seeding-cylinder into the drills in the usual manner.

The tubes themselves, however, differ from those heretofore constructed, which have been made cylindrical throughout their entire length, while cast-iron or tin funnels have been used to conduct the seed from the seeding-cylinder, into the tubes; but, instead, the tube J and funnel J' are made of separate pieces of gum, the funnel having an elongated flaring-shaped mouth, j , at one side, so as to fit directly beneath the case of the seeding-cylinder, as shown in figs. 7 and 15, and be clamped thereto by a clasp, k , hinged eccentrically to the case b , so that it will, when turned up, leave a space between it and the case for the insertion of the projecting end j of the funnel, and, when brought down hard, it will clamp and bite the end j of the funnel securely against the fixed case b , and thus the flexible tube J is suspended directly to the case of the seeding-cylinder, by which I am enabled to build the drill-box lower down, or closer to the frame, and lessen the diameter of the gearing-wheels, dispensing also with the ordinary cross-bar, tin funnels rendering the whole machine more compact, and allowing the tubes to bend freely throughout their whole length, instead of, as heretofore, to break the tube just below the cross-bar, but by dispensing with the cross-bar and

rigid funnels, the drills may strike the tubes higher up without any danger of breaking them.

By thus making the tubes and funnels in one piece, and clasping them to the case, they may be removed at pleasure, and replaced with facility, without disturbing any other part of the machine.

The fertilizing-chamber is provided with slides l , having openings 2 therein, corresponding with those in the bottom of the hopper, and they are fitted into guides, so that they may slide back and forth, and be adjusted to increase or diminish the area of the openings, to regulate the discharge of the fertilizer from the hopper, which fertilizer is conducted, by a gum tube, 10, figs. 2 and 10, into the flaring mouth of the tube J continuously with the feed.

In adjusting these slides l , they are moved in opposite directions by means of a hand-lever, l^2 , pivoted within the hopper, and having two slots 3 3, represented in fig. 16, therein, into which fit pins or projections 4, from the slides.

The slots are arranged eccentrically on each side of the pivot, so that when the handle of the adjusting-plate is turned in one direction, the slides are moved so as to uncover the openings and increase their size, and when moved in the opposite direction, the area of the openings is lessened.

To prevent the openings in the slides from being choked, and to insure the regular feed of the fertilizer, I have arranged a series of vibrating feeders, m , within the hopper, one to each opening.

The feeding-arms are secured to a horizontal rock-shaft, m^2 , fitted in boxes m^3 , so as to be removed therefrom whenever required, the boxes having open ends or sockets, into which the ends of the shaft m^2 fit, and are secured by a pin, n , passing through the sides of the boxes, just over the ends of the shaft.

The boxes are fitted with round shanks, n^2 , and are secured in the ends of the hopper F^3 , so as to oscillate with the shaft.

The feeders m are forked at their lower ends, so as to stride the openings in the slides, as shown in fig. 2, so that each fork m^2 of the arm will just move half way across the opening, instead of a single arm moving back and forth entirely over the opening, as heretofore, which is objectionable, because the arm is liable to catch a gravel just against one side of the opening, in crossing either way, and break or bend the arm; but by feeding both ways just to the centre of the opening by straddling arms, this difficulty is avoided, the feed rendered more certain, and by less range of motion of the double than with the single arm.

The straddling feeders are of such a form that when moving toward the centre of the opening, they push the fertilizer before them into the opening, and when moving back, they pass through it without much resistance.

The motion of the fertilizing feeding-arms is derived from gearing located at the outside of one end of the hopper, and the shank n^2 of one of the oscillating boxes m^3 extends through the hopper for that purpose, as shown in fig. 10, and is fitted with a segment of a pinion, o , into which matches the segment of another pinion, p , on a fixed stud, which also carries an arm, q , whose lower end has a small roller, q^1 , which fits into an elliptical groove, q^2 , on the inner face of a cog-wheel, K , secured on the end of the shaft G of the seeding-cylinders, as shown in fig. 9, and which receives its motion from a cog-wheel, K^1 , on the hub of the driving-wheel, through an intermediate pinion, K^2 .

From the foregoing it will be observed that the driving cog-wheel K causes the grooved cogged wheel K of the cylinders to revolve also, and causes the small roller q^1 of the arm q to traverse the elliptical groove q^2 , and to vibrate the arm q , which, being fixed to the segment-pinion p , also causes it to vibrate, which in turn vibrates the segment-pinion o of the rock-shaft

m^2 , and thus vibrates the feeding-arms m , and affords a simple method of overcoming the dead-centres, and obtaining a constant feed of fertilizers.

The segment-pinion o of the rock-shaft m^2 is thrown into and out of gear with the segment-pinion p , by means of a clutch-lever, r , as shown in figs. 9 and 10.

The mechanism for converting the seeding-machine into a corn-planter consists of certain devices for dropping the corn in hills or check-rows, according to horizontal distance.

This is accomplished by means of an expansible pulley, mounted upon a horizontal shaft, L , secured in bearings in the frame beneath the hopper, which pulley is expanded and contracted by means of a pendent weight, suspended from near the front of the frame, and a horizontal hinged suspension-bar, to which the drill-tubes are attached, for carrying the rubber tubes of the drills, so as to receive the corn directly from the feeding-cylinders, and drop it at proper intervals, according to the revolutions of the expansible pulley.

The expansible pulley M is located near the middle of the frame, and is made in sections s , grooved to receive a cord or chain, N , which it drives.

Each section of the pulley is hinged to the opposite ends of arms t , whose other ends are hinged in like manner to two bearing-heads or boxes u , mounted upon the shaft L , on opposite sides of the sectional pulley M , as shown in figs. 3 and 5, so as to slide thereon, and approach nearer to or recede further from the said pulley, and thus increase or diminish its diameter.

The sections s of the pulley thus secured are of a size to leave spaces between them, and thus interrupt the continuity of the circumference of the pulley, and they are held in position, so as to expand and contract in radial lines, by means of two circular plates or disks v , arranged vertically upon the shaft L , and turning therewith.

These plates v are provided with radial slots v' , into and through which the arms t of the sectional pulley M project, and these plates thus form a case, to maintain the sections of the pulley in proper relation with each other, because being fixed to their hubs u , on the shaft L , will cause the arms t to rise and fall within the slots, as the said sliding heads are brought nearer to or carried further from each other.

This pulley is revolved by a pinion, 13, fig. 9, on the shaft L , matching with the driving-gear K^1 , and communicates motion, by means of the endless cord N , to a revolving wheel, O , carrying a tooth, z , upon its circumference, which latter is arranged to strike upon a small toothed wheel, P , on a horizontal rod, P^1 , which carries winged wheels, P^2 , fig. 6, located in the intermittently-feeding hoppers P^3 of the hinged suspension-bar Q .

The toothed wheel O is placed upon a short shaft, arranged between the sectional pulley and the intermittently-feeding chambers, and is mounted in bearings in a metallic frame, R , secured at its front ends to a cross-timber of the frame, and to the brace-rod E of the short axles.

The endless cord N of the sectional pulley M passes around a small pulley, w , on the face of the toothed wheel O , and in order that the cord may expand and contract with the sectional pulley, it is passed over two small fixed pulleys, $w^1 w^2$, and under a central small pulley, w^3 , having its journals fitted in slots in a hanger, w^4 , secured to the under side of the hopper, so that the last-named pulley may rise within said hanger, and fall by its weight, to take up any slack in the endless cord, or let it out, with the expansion and contraction of the sectional pulley, as shown in figs. 2 and 4. Its tautness is thus always insured, to maintain the regularity of the revolution of the toothed wheel.

The suspension-bar Q is located in the rear of the short axles D , and is hinged to the brace-rod E by two arms S , fig. 3, which also carry the intermittently-dropping corn-chambers P^3 .

These chambers are provided with four wings, which are secured by hubs to the ends of the horizontal rod P^1 , upon which the intermittently-revolving small toothed wheel P is secured.

The corn-chambers are provided with necks above and below their winged hubs, in which are secured the rubber tubes J , the upper one having its rubber funnel-shaped mouth J' secured by the clasp k of the case of the seeding-cylinder, while the lower one leads into the drill-tubes, and thus a communication is effected directly between the continuously-revolving seeding-cylinder and the intermittently-revolving wings of the corn-chambers.

The small wheel P , on the rod of the intermittently-revolving wings, is provided with four teeth or projections, corresponding in position radially with the feeding-wings P^2 , and they are arranged in such proximity to the tooth z of the wheel O , that each revolution of the wheel will bring the tooth thereof in contact with one of the teeth of the horizontal rod P^1 , and thus turn it a quarter of a revolution, so that the grains of corn resting upon the wing in each chamber will be discharged through the opening in the lower side of said chamber, and at the same time bring the next wing in a position within the case of the chamber, to form a stop to the descending corn, in readiness to be turned to drop the next hill.

The toothed wheel P may be held from presenting its teeth irregularly to the action of the tooth z , by a spring, 14, figs. 2, 3, and 5.

In order to prevent the radial wings from binding within the corn-chambers P^3 , in discharging the corn, I make the rear sides P^4 thereof, opposite the wings, hinged, and held close against the side of the case by a spring, or the hinged side may be weighted for that purpose, so as to form a slightly-yielding side of the chamber, and thus prevent the possibility of the wings becoming locked by a grain of corn between it and the case, which would cause the wings to bind and interrupt their turning.

The horizontal bar Q of the intermittently-feeding chambers is suspended by two chains, 15, figs. 2 and 3, to the two diagonal beams of the frame, and being also hinged, by the arms S , to the brace-bar of the axles, it must, therefore, rise and fall in the arc of a circle, maintaining always its four-toothed wheel in a position to be struck by the revolving single-toothed wheel, so that the flexibility of the suspension-bar cannot interfere with the regular intermittent rotation of the winged feeders.

It will be observed that the devices thus arranged and operating would plant corn irrespective of regular horizontal distances. To compensate for this, and to drop the hills of corn at regular intervals apart, irrespective of the undulations on the surface of the ground, I arrange an automatic device, consisting of a pendent weighted lever, T , suspended from a horizontal rod, y , secured to the under side of one of the front timbers of the frame, so that it will hang downward, and swing back and forth upon said rod.

This rod y is arranged to turn in its bearings by the movement of the pendent weight, and carries a cam or groove of peculiar shape, which is connected to the sliding bearings u , of the sectional pulley M , by means of two arms somewhat in the form of a pair of tongs, having two long, 16, and two short ends, 17, as shown in figs. 1 and 5, and pivoted, near their short ends, to the under side of one of the front timbers of the frame.

The rod of the pendent weight is on a horizontal line with the shaft of the sectional pulley, and the long ends 16 of the pivoted arms are forked, so as to fit into grooves, like a clutch, in the sliding hubs u , of

the sectional pulley, while the short ends 17 of these arms fit into the grooves of the cam, so as to embrace the sides of a double frog-shaped cam, z , united at the base of its angles, so that their apices are at the extreme end of the groove.

When the machine is moving over a level surface, the short ends 17 of the arms occupy a position within the groove on either side of the widest part of the cam, and, therefore, do not change the distance between the intervals of planting, as the sectional pulley will maintain a regular and uniform degree of expansion; but in ascending or descending a hill, the surface-distance becomes greater than a horizontal, and it becomes necessary, in order to equalize the two distances, to reduce the diameter of the sectional pulley, and thereby diminish its action upon the toothed wheel, so as to cause it to revolve with a less degree of rapidity. Upon level ground, therefore, the short ends 17 of the arms occupy the position before described, but in ascending or descending a hill, they converge either toward one point or the other of the double frog-shaped cam z , and, in either case, contract the pulley, according to the extent of the contraction of the short ends of the arms; for, it will be seen, the pivot of the arms being fixed, the opening or closing of their short ends, 17, must open or close their long ends, 16, proportionately, and thus increase or diminish the diameter of the sectional pulley through its hinged arms, so as to increase or diminish the revolution of the toothed wheel. To effect this, therefore, the pendent weight T must have a fixed connection upon the rod y of the operating-cam, which is made by means of an arm, 18, on said rod, having its lower end notched, so as to fit into corresponding teeth in a shoulder on the upper-end of said pendent weight, as shown in figs. 2 and 4, and thus lock the latter to its axis; and, the pendent lever having sufficient weight, it is plain, that as its lower end swings toward the front in descending, or toward the rear in ascending a hill, it will, of course, so operate the cam z as to contract the pulley M , because the arms 17 will be caused to pass within the groove, toward one or the other of the apices of the cam, whether the weight swing toward the front or the rear, and thus effect the intermittent dropping of the corn as regularly, and at the same distances, as if the machine were travelling over a level surface.

The connection of the weighted lever with its axis, while it is fixed, is also capable of adjustment, so as to be set at different inclinations with the frame, by its notched arm 18, when operating upon ground having quite steep hills, so that the weight will the more readily turn the cam the required distance to contract the pulley suddenly and sufficiently.

The pendent weight is held in its locked position by a spring fixed to the axis of the weight, so as to bear it constantly against the fixed arm 18.

In order that the expandible pulley may be made to act suddenly, to correct any error which may have arisen, from any cause, in planting, in equal distances, on a level surface, I arrange a foot-lever, 19, upon the axis of the cam, so that the attendant, from his seat, may use his foot against the lever, thereby contracting the pulley, and thus correcting any irregularity in the distance between the hills.

This mechanism for planting corn is secured to the machine, so that it may be removed entirely therefrom when the machine is used for planting seed continuously.

An automatic drill-tooth marker may be used in connection with this machine; but, as the automatic expandible and contractible pulley is absolutely correct in planting corn in check-rows, it is not deemed essential to use a marker in connection therewith.

Having thus described my invention,
I claim—

1. In combination with short axles D D , the diagonal beams A^2 , of the frame A , arranged above the axles, substantially as before described.

2. The combination of the short axles D D , the diagonal beams A^2 , and the frame A , with the horizontal brace-rod E , arranged beneath and connected with the axles D , substantially as before described.

3. The elastic or yielding seeding-cylinder, substantially as before described.

4. An elastic and inelastic seeding-cylinder, constructed substantially as before described.

5. An elastic seeding-cylinder, having a fixed axis, and constructed with encircling iron bands and ribs, substantially as before described.

6. The addition, to the gum tube, of a flaring hopper-shaped mouth, also of gum, thus forming a pliable and yielding hopper, and facilitating the transmission of grain to the tube, substantially as before described.

7. The funnel or flaring mouth of the conducting-tube, secured to the case of the seeding-cylinder by means of a clasp, so that the tube may be removed at pleasure, substantially as before described.

8. The combination of a conducting-tube and funnel with the case of the seeding-cylinder and the hinged securing-clasp, constructed and arranged substantially as before described.

9. The double drag-bars, hinged, separately and directly, to the drilling-tube, and to the frame, thereby doubling the strength of the drag-bars, while two of them also serve as the tripping-levers of the drill-tube, substantially as described.

10. The adjustable notched carriage i^2 , of the inner drag-bar I^2 , in combination with the adjustable seat i^2 , of the spring h , secured thereon, as described.

11. The stirrup i , capable of adjustment horizontally on the outer drag-bar I^2 , to which it is also locked vertically, in combination with the adjustable carriage i^2 and the adjustable seat i^2 , substantially as described.

12. The rock-shaft of the fertilizing-hopper, secured in oscillating seats or boxes, so as to allow it to be removed, with its arms, at pleasure, substantially as described.

13. The vibrating feeding-arms m , divided, so that each arm will form a pair, m^2 , and vibrated, so that each arm of the pair will only pass over one-half of the opening, to feed the fertilizer, substantially as described.

14. The combination of the removable rock-shaft m^2 and its oscillating boxes m^2 with the feeding-arms m , constructed and arranged substantially as described.

15. The fertilizing-arms m , operated by means of the elliptical groove or cam q^2 , in connection with the radial arm q and the segment-pinions o and p , as herein described.

16. The slides of the fertilizing-hopper, operated, so as to increase or diminish the feed of the fertilizer, by means of the eccentrically-grooved pivoted plate, as herein described.

17. The expandible and contractible pulley, constructed and operating substantially as described.

18. The expandible and contractible pulley, constructed in sections, in combination with the arms, to which they are hinged, substantially as described.

19. The sectional pulley, expanded and contracted, automatically, by means of a pendulous weight, or its equivalent, substantially as described.

20. In combination with a sectional pulley and its automatically-operating weight, the cam and the pivoted arms, arranged and operating substantially as before described.

21. The pendulous weight, made adjustable, in the manner and for the purpose herein described.

22. The expanding and contracting pulley M , in combination with the toothed wheels O and P , operating substantially as before described.

23. The combination of a hopper, for feeding con-

tinuously, with receiving-chambers, for discharging the corn at intervals, according to horizontal distance, substantially as before described.

24. The intermittently-feeding corn-chambers, suspended by means of a horizontal hinged bar, substantially as before described.

25. The combination of the intermittently-feeding wings of the corn-chambers with the toothed wheels O P and the sectional pulley, substantially as before described.

26. The sides of the intermittently-feeding chambers, hinged, so as to form a yielding side thereto, for

the purpose of preventing the choking of the chambers, substantially as herein described.

27. The combination of an expansible and contractible pulley with a fixed case or guiding-plates and flexible supporting-arms, substantially as described.

28. The combination of the pendulous weight T, cam z, expansible and contractible pulley M, with the foot-lever 19, for the purpose described.

SAML. M. FIREY.
